UNITED STATES PATENT OFFICE.

BENGT M. W. HANSON, OF HARTFORD, CONNECTICUT.

SHAPER FOR GRINDING WHEELS.

Application filed October 23, 1920. Serial No. 419,120.

To all whom in may concern:

Be it known that I, BENGT M. W. HANSON, a citizen of the United States, and a resident of Hartford, in the county of 5 Hartford, State of Connecticut, have invented certain new and useful Improvements in a Shaper for Grinding Wheels, of which the following is a specification.

This invention is designed for shaping 10 the edge of a grinding wheel. The embodiment of the invention, here selected for purpose of illustration, will be described with reference to its use for shaping or re-truing the edge of a grinding wheel em- 15 ployed in operating on a thread of the Whitworth type and to which use the present device is peculiarly adapted, but it is to be understood that the present disclosure is by way of illustration only, it not being in- 20 tended to limit the invention to this particu- 25 lar use and it being susceptible of other embodiments than that herein shown.

The object of the invention is to provide a device for shaping the edge of a grinding 25 wheel so that it conforms with the greatest accuracy and precision in contour and size to the cut to be taken in the work.

In the accompanying drawings:

Fig. 1 is a top plan view of so much of a 30 grinding machine as is necessary to illustrate the present invention.

Fig. 2 is a side view of the carriage on which the device of the present invention is mounted.

Fig. 3 is an end view of the shaper.

So much of the grinding machine as is illustrated in the drawings is shown more or less diagrammatically as the particular construction thereof forms no part of the 40 present invention. In the present case, this machine has a bed *a* carrying a grinding wheel *b* driven by a belt *c*. *d* is a carriage movable to and from the grinding wheel by the hand wheel *e*, and *f* is a cross slide on the carriage and supporting the shaper of the present invention.

The shaping tool in the present illustrative disclosure is in the form of a roller 10 longitudinally fluted as at 11 and having 50 one or more circumferential grooves 12 conforming in cross section to the precise shape and size of the cut to be taken in the work. Fig. 3 shows the roller as it is in actual practice and from this figure it will be seen 55 that there are a relatively large number of

flutes 11 so as to give to each groove 12 a multiplicity of edges 13. In Figures 1 and 2 the roller, for purpose of convenience in illustration, is shown as having a fewer number of flutes than are present in actual practice. In the present instance the shaper has two grooves 12 but the number may be varied, preferably there being more than one to effect economy in manufacture, to eliminate the necessity of frequent replacements, and to permit of re-truing of the 60 grooves 12 by the grinding wheel as herein-after described. In order to insure that the grinding wheel and the roller while operating upon one another are in proper relative positions, the roller has a free movement axially. By way of example, the roller may be mounted on a spindle 14 on which it is freely rotatable and along which it may freely float longitudinally.

To finally shape the edge of the grinding wheel to the precise size and contour desired, the carriage *d* is moved forward to bring the roller up to the grinding wheel, and when the surface of one of the grooves 80 12 engages the grinding wheel, the roller will float or adjust itself longitudinally into such position that the groove and grinding wheel are in exact alinement. The grinding wheel, while the roller is being urged there- 85 against, is slowly rotated as by manually pulling on the belt *c* causing, of course, the roller to rotate in the opposite direction at substantially the same peripheral speed. The edges 13 provided at the intersections of 90 the flutes and grooves of the roller will have a crushing or picking action on the grinding wheel that will rapidly bring the edge thereof to the exact shape of the groove in the roller, which shape, as previously stated, 95 corresponds precisely with the Whitworth thread to be cut. Each edge 13 as it is brought into engagement with the wheel have a very slight pecking or knocking action thereby breaking off of the wheel very small 100 fine particles, and while the effect of the engagement of each edge on the wheel is ex- 105 tremely slight, the aggregate effect of bringing these edges repeatedly in rapid succession against the wheel will be very quickly noticeable. It will be noted that as the roller is free to float or move longitudinally, it automatically adjusts itself to the proper position, and during the re-truing operation there are no thrusts or forces tending to 110

cause the roller to cut unevenly on the faces of the cutting edge of the grinding wheel.

After one groove of the roller becomes worn due to repeated use, the cross slide 5 may be moved to bring another groove 12 into position for retruing the grinding wheel, and after the grinding wheel is trued by the second groove, it may be employed to operate upon the worn groove to retrue that 10 groove to its correct shape and size. When retruing a groove 12 the grinding wheel is rapidly rotated, and the roller is slowly rotated in the same direction so that the roller and the wheel at their points of engagement, 15 are moving in opposite directions at unequal speeds. Thus it will be seen by following this method the roller and grinding wheel may be employed to retrue one another.

20 I claim as my invention:

1. In an apparatus of the character described, a rotary grinding wheel fixed against axial movement, a support, a shaft mounted therein in parallelism with the 25 axis of said wheel, and a longitudinally fluted roller on said shaft and having a circumferential groove corresponding to the cut to be taken by said wheel, said roller having free axial movement whereby it may 30 freely float longitudinally to accommodate itself in proper relation to said wheel.

2. A device for giving to the active edge

of a grinding wheel a shape corresponding to that of a Whitworth thread to be cut and comprising a single piece metal roller having 35 a circumferential groove corresponding in shape to the cut to be taken by the wheel, said roller being longitudinally fluted to form transversely extending cutting edges.

3. In combination, a grinding wheel and 40 a roller having a pair of longitudinally spaced apart circumferential grooves corresponding to the cut to be taken by the wheel, the walls of said grooves being interrupted at intervals as described, means for 45 longitudinally adjusting said roller so as to bring either of said grooves therein into operative relation to the wheel, and means for feeding said wheel and roller relative to 50 one another during retruing operations.

4. In combination, a grinding wheel and 55 a roller having a pair of longitudinally spaced apart circumferential grooves corresponding to the cut to be taken by said wheel, the walls of said grooves being interrupted at intervals as described, a support for longitudinally adjusting said roller so as to bring either of said grooves therein 60 into operative relation to the wheel, and means for feeding said wheel and roller relative to one another during the retruing operations, said roller being mounted for free floating endwise movement.

BENGT M. W. HANSON.
